UNITED STATES PATENT OFFICE

162,662

TOY PISTOL

Domenick Ippolito, Glendale, Calif.

Application December 2, 1950, Serial No. 13,247

Term of patent 14 years

(Cl. D34—15)

To all whom it may concern:

Be it known that I, Domenick Ippolito, a citizen of the United States, residing at Glendale, in the county of Los Angeles and State of California, have invented a new, original, and ornamental Design for a Toy Pistol, of which the following is a specification, reference being had to the accompanying drawing, forming part thereof.

In the drawing

Fig. 1 is a top plan view of the toy pistol, showing my new design;

Fig. 2 is a side elevation looking in the direction of the arrow 2 of Fig. 1;

Fig. 3 is a front elevation looking in the direction of the arrow 3 of Fig. 2;

Fig. 4 is a rear elevation looking in the direction of the arrow 4 of Fig. 2.

I claim:

The ornamental design for a toy pistol, as shown.

DOMENICK IPPOLITO.
